UNITED STATES PATENT OFFICE

CYRUS M. WARREN, OF BROOKLINE, MASSACHUSETTS.

ROOF, ROOFING FABRIC, AND MECHANISM FOR MANUFACTURING THE SAME.

SPECIFICATION forming part of Letters Patent No. 351,948, dated November 2, 1886.

Application filed November 30, 1885. Serial No. 184,354. (Specimens.)

To all whom it may concern:

Be it known that I, CYRUS M. WARREN, a citizen of the United States, residing at Brookline, in the county of Norfolk and State of Massachusetts, have invented a new and useful Improvement in Roofing Fabric and Machines for Manufacturing the Same, of which the following, taken in connection with the accompanying drawings, is a full, clear, and exact description.

My invention relates to improvements in roofing fabrics and in the mechanism for manufacturing the same.

The object of my invention is to provide a thin and flexible roofing fabric which will be stronger than that commonly used, and which will have its edges protected, so that the pitch or other water-proof material placed between the layers of fabric will not pass out of the ends of the roll or from between the layers of paper or felt which compose the fabric.

Referring to the drawings, Figure 1 is a longitudinal sectional view of the machine for manufacturing my improved roofing-felt. Fig. 2 is a top or plan view of a portion of the machine, showing the devices which fold the wider strip over the edges of the narrower strip.

A indicates a roll of dry roofing-felt or paper mounted in suitable bearings at the side of the tank B, said tank being designed to hold coal-tar or other water-proof material, and may be provided with a steam-coil or other suitable device for heating and keeping the coal-tar in a fluid condition, so that it will be readily absorbed by the paper or felt strip A', which is passed under the roller B', located in the tank B, said roller being adjustable in guides b. The rear side of the tank B is flared, as shown, so as to receive the excess of coal-tar which is pressed out by the rolls C C, mounted in the standards B".

E is a tank, mounted on suitable supports, in which the roller D is mounted, said tank being designed to hold coal-tar, pitch, or a compound of the residuum of petroleum and asphaltum or other water-proof material, and provided with any suitable heating device for keeping the pitch in a fluid, semi-fluid, or molten condition. The roller D is partially immersed in the pitch contained in the tank E, and as the web of felt A' is drawn over the

roll it revolves the same and deposits on the under side of the felt a coating of pitch, the thickness of said coating being regulated by the gage-bar b, which is made adjustable in any suitable manner in the frame A".

F is a roll of Manila rope paper, mounted in suitable bearings in the frame of the machine, over which the coated web of felt A' passes, and is joined by the continuous webs of Manila paper, after which the felt and paper pass under the guide-bar c, over the driving-roll G, and under the guide-bar c', which tends to join the thin sheet of Manila paper firmly to the layer or sheet of felt, and at the same time lay or press the two sheets evenly together, so as to avoid wrinkling or the buckling of the paper. The sheet or strip of thin Manila paper is wider than the sheet of felt or roofing paper A', and when the two sheets are joined together the edges of the thin sheet project beyond the edges of the strip of felt A', as shown in a portion, Fig. 2. d are blocks secured to the frame of the machine, having folding devices d', through which the edges of the compound sheet C are passed. The folding devices d' are so formed that the edges of the thin sheet will be turned over and folded down on the top of the heavy sheet of felt, thus preventing the pitch which has been applied on the under side of the felt by the roller G from oozing out between the layers of fabric and cementing the different layers or convolutions together when rolled up on the roller I, as would be the case if the edges were not protected in the manner indicated. After the edges of the thin sheet have been folded over onto the felt sheet it passes under the guide-bar c, over the friction-roller H, and around the roller I, on which the fabric is wound, said roller I being turned by frictional contact with the power-driven roller H. The rolls C are made hollow, and adapted to be heated by steam, so that the coal-tar will be driven into the felt and the surface rendered smooth and dry.

It will be noticed that in the mechanism and operation just described the felt is saturated with coal-tar, so as to render it impervious to water, is coated on one side with pitch, and a thin sheet of Manila or other strong paper secured to one side, so as to overlap the edges of the felt in one and the same opera-

tion, thus making a finished product of great strength and pliability, while at the same time it is light and easily laid on the roof-boards.

I do not limit myself to the use of Manila rope paper and felt in the manufacture of roofing fabric; but instead of these or either of them I may employ any thin and cheaper paper, if preferred, for any purpose. Nor do I confine myself to using Manila rope paper in its dry or natural condition, for I may use with good results a previously tarred or saturated Manila rope paper. I prefer, however, to use the former, and when desirable that it should be saturated I accomplish this by rolling up the freshly-made fabric while hot, for the Manila rope paper, being so thin, will then absorb in the hot roll enough of the cement for complete saturation.

Having thus described my invention, what I claim is—

1. A roofing or sheathing fabric composed of two sheets of roofing paper or felt, one of said sheets being wider than the other and the edges of the wider sheet being turned over the edges of the narrower sheet, as set forth.
2. A roofing or sheathing fabric composed of heavy roofing paper or felt previously saturated with coal tar, and a sheet of thin strong paper wider than the saturated sheet cemented to one side thereof with a layer of coal-tar pitch or other adhesive water-proof material, as set forth.
3. A roofing or sheathing fabric composed of a sheet of saturated felt, and a wider sheet of Manila rope paper somewhat wider than the felt sheet, the two sheets being joined together by a layer of coal-tar pitch, the edges

of the Manila paper being folded over the edges of the felt sheet, as described, whereby the pitch is prevented from oozing out through the edges of the fabric, as set forth.

4. A machine for the manufacture of roofing fabric, consisting of a tank for saturating the felt, a pair of rolls for removing the excess of coal-tar from the felt, a roller revolving in a tank for coating one side of the felt with pitch, and a roll of thin dry paper wider than the roll of felt mounted in the path of the coated felt, so that it will be joined to the coated sheet of felt, and devices, substantially as described, for turning the edges of the wider sheet over onto the edges of the narrower sheet, as set forth.

5. In a machine for manufacturing roofing fabric, the blocks *d*, having the folding devices *d'*, adapted to receive and turn the edges of the sheet *C* over onto the sheet of felt *A'*, as set forth.

6. In a machine for manufacturing roofing fabric, the gage-bar *b*, in combination with the coating-roller *D*, as set forth.

7. In a machine for manufacturing roofing or sheathing fabric, a guide bar or roller, *e*, in combination with a friction roller, *H*, substantially as set forth.

8. In a machine for manufacturing roofing fabric, the guide bars or rollers *c c'*, in combination with the driving-roller *G*, substantially as set forth.
